UNITED STATES PATENT OFFICE.

EDWARD A. BROWN, OF FORT WORTH, TEXAS.

VENTILATOR.

Application filed May 3, 1923. Serial No. 636,454.

To all whom it may concern:

Be it known that I, EDWARD A. BROWN, a citizen of the United States, residing at Fort Worth, in the county of Tarrant and State of Texas, have invented new and useful Improvements in Ventilators, of which the following is a specification.

My invention relates to ventilators and more particularly to such as are especially fitted for use in the windows of railway cars although capable of other adaptations. An important object of the invention is to provide an adjustable ventilator of this kind which may be conveniently carried in a traveling bag and readily applied or removed from a window.

A further object of the invention is the provision, in connection with a device of the character set forth, of a novel and improved means for securing the device in position without marring or damaging any portion of the window.

The invention also has for its object to furnish a ventilator of the kind stated which is very simple in construction, highly efficient in use and which may be cheaply manufactured.

The above and other objects are attained by means of certain novel features of construction and arrangement of the various parts as will be more fully described hereinafter and pointed out in the appended claims.

In order to obtain a better understanding of the invention, reference is had to the accompanying drawings, forming a part of this specification, wherein the preferred embodiment of the invention is disclosed and in which similar reference characters have been used to designate like parts throughout the several views.

In the drawings:—

Figure 1 is a perspective view of a portion of the interior of a railway coach showing the ventilator in use;

Fig. 2 is an elevation of one form of adjustable clip;

Fig. 3 is a central longitudinal section through Fig. 2;

Fig. 4 is a view partly in section and partly in elevation of a modified form of clip, and

Fig. 5 is an end view thereof.

Referring specifically to the drawing, numerals 6 and 7 denote the lower sash rail

and sill, respectively, of a window of a railway coach between which is adjustably positioned a ventilator in the form of a plate or shield 8. This plate may be of aluminum, cardboard or any other suitable material which may be found adaptable. A newspaper or magazine can be used if desired, my invention residing particularly in the pair of clamps for engaging the shield and window sash rail for holding the device in position.

The clamping means comprises a pair of substantially U-shaped clamps 9 and 10 of sheet metal which are pivotally connected at their closed back portions intermediate their ends by means of a bolt and nut 11 and 11a.

The upper clip 9 is adapted to engage and receive the bottom portion of the lower sash rail 6, the inner arm of said clip being inwardly curled to form a finger grip 12 for facilitating disengagement of the sash rail while the outer arm of said clip has an aperture 13 near its upper edge to permit hanging of the assembly upon a convenient nail or hook when not in use.

The lower clip 10 serves to engage the top edge of the shield 8 to hold the same. This clip 10 is also provided with apertures 14 and 15. The apertures 14 are preferably included in this lower clip to permit the insertion of some instrument or lever for spreading the arms of the clip, while the aperture 15 may be used in connection with the adjacent aperture 14 as a finger grip in manipulating the clip 10.

Referring to Figs. 4 and 5, wherein a modification of the invention is disclosed, it will be noted that I have formed the clips 9 and 10 of a hinged construction and have provided springs 16 of sheet metal for maintaining the arms of the clips in holding position. The hinges for the arms of the respective clips are denoted at 17, each arm of the clips being preferably provided with two hinges as shown in Fig. 4 to add firmness to the assembly. Each of the spring members 16 extends throughout the length of its clip and is provided with an aperture intermediate its ends through which the bolt 11 passes for pivotally maintaining the sections in assembled relation.

From the foregoing description read in connection with the accompanying drawing, the construction of the invention will be readily understood. The device can be

2
quickly applied to the lower sash rail 6 and the lower clip 10 can be adjusted in a manner to suit the occupant of the seat. By the adjustment of the device as shown in Fig. 1, stale air from the car will be permitted to pass out between the shield and the rear portion of the window frame, while fresh air from without will enter through the space in advance of the shield 8. In the position shown in Fig. 1 the occupant of the seat will be protected from cinders and other particles. Should it be desired to subject the car to a strong draft a slight turn of the shield 8 will throw direct a strong current of air into the car upon the occupants of the adjacent seat.

In accordance with the patent statutes I have described and illustrated the preferred embodiment of my invention, but it will be understood that various changes and modifications can be made therein without departing from the spirit of the invention as defined by the appended claims.

I claim:

- 25 1. The combination with a window sash of a ventilator including a relatively rigid shield extending in the direction of the length of said sash beyond one rail thereof, a sash attaching means for said shield comprising sash and shield engaging members, and a pivotal connection between said members extending in the direction of the length of said sash.
2. A window ventilator for railway

coaches including in combination with the bottom rail of a window sash, a relatively rigid shield extending in the direction of the length of the sash and beyond said bottom rail, sash attaching means for said shield comprising two pairs of hinged oppositely directed clamping members the arms of one being adapted to embrace said sash rail while the arms of the other are engageable with said shield, a pivotal connection between said clamping members arranged transversely with respect to the hinges thereof, and means interposed between said clamping members adapted to maintain the arms thereof in clamping position.

3. A window ventilator for railway coaches including in combination with the bottom rail of a window sash, a relatively rigid shield extending in the direction of the length of the sash and beyond said bottom rail, sash attaching means for said shield comprising two pairs of hinged oppositely directed clamping members the arms of one being adapted to embrace said sash rail while the arms of the other are engageable with said shield, connecting means for said clamping members, means interposed between said clamping members adapted to maintain the arms thereof in clamping position, said means being retained in place by said connecting means.

In testimony whereof I affix my signature.

EDWARD A. BROWN.
